UNITED STATES PATENT OFFICE.

LEVI BERGER AND WILLIAM H. BERGER, OF PHILADELPHIA, PA.

DESIGN FOR A SAUCEPAN-HANDLE.

SPECIFICATION forming part of Design No. 12,582, dated November 29, 1881.

Application filed September 10, 1881. Term of patent 7 years.

To all whom it may concern:

Be it known that we, LEVI BERGER and WM. H. BERGER, citizens of the United States, residing at Philadelphia, in the county of Philadelphia and State of Pennsylvania, have invented a new and useful Design for Saucepan Handles, of which the following is a specification.

Our invention relates to designs for saucepan-handles which are riveted to the body of the pan, and is fully illustrated in the accompanying drawing, of which the figure is a view of the back of the handle, showing the design. Heretofore saucepan-handles have been made with the handle proper of a flat piece of sheet-iron, and is liable to be bent in lifting the pan from a stove.

The leading features of our design consist in making a depression in the handle, and by connecting the two edge portions of the fenestrated handle by a bridge of metal to strengthen it and prevent the destruction of the handle by twisting or torsion. We make a handle for saucepans of cast metal, consisting of an edge piece on either side of the handle, the center being left open for purposes of lightness and economy. Bridging across from one to the

other of these edge pieces is made a band, *a*, or bridge of metal, for the purpose of strength. The edge pieces are brought together at the base, and are continuous with the neck or shaft of the handle. Along the middle of the neck *B* is a raised ridge, which runs down onto flange *C* of the handle, and then spreads out in two curved ridges, which encircle the rivet-holes *d*. At the intersection of the two curved ridges on the flange *C* is an elongated point, terminating at the lower margin of the flange *C*. The flange *C* consists of a broad flattened portion, having two rings bounded each by an ogee curved line, and a terminal portion bounded by a curve and two straight lines. The wings have their upper edges bounded by straight lines at right angles with the shaft or neck.

We claim—

The design for a saucepan-handle, having a fenestrated handle, *A*, with a central bridge or band, *a*, as herein shown and described.

LEVI BERGER.
WM. H. BERGER.
